(57) **CLAIM**

The ornamental design for a medical patch, as shown and described.

DESCRIPTION

FIG. 1 is a front view of a medical patch of the present invention, also showing instructions for use.

FIG. 2 is a rear view of the medical patch of FIG. 1.

FIG. 3 is a top plan view of the medical patch of FIG. 1.

FIG. 4 is a bottom view of the medical patch of FIG. 1.

FIG. 5 is a right side view of the medical patch of FIG. 1.

FIG. 6 is a left side view of the medical patch of FIG. 1; and, FIG. 7 is an enlarged 7-7 sectional view of the medical patch of FIG. 1.

The features shown only in dotted lines (. . .) depict environmental subject matter only and form no part of the claimed design.

The features surrounded by dashes and dotted lines (. . .) are part of the claimed design.

1 Claim, 7 Drawing Sheets
